(57) **CLAIM**

The ornamental design for a shower head, as shown and described.

DESCRIPTION

FIG. 1 is a front and top perspective view of a shower head, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of area 9 circumscribed within FIG. 1; and,

FIG. 10 is an enlarged detail view of area 10 circumscribed within FIG. 2.

The evenly spaced broken lines and all areas within depict portions of the shower head that form no part of the claimed design. The dot dash dot broken lines in FIGS. 1, 2, 9 and 10 depict the boundaries of the enlarged detail views and form no part of the claimed design.
